COMBINATION TAP WRENCH AND HOLDER

William E. Cowley, Louisville, Ky., assignor to American Saw and Tool Company, Louisville, Ky., a corporation of Kentucky

Filed Dec. 8, 1958, Ser. No. 53,697

Term of patent 14 years

(Cl. D54—16)

Figure 1 is a front perspective view of a combination tap wrench and holder, taken from the top, showing my new design;

Figure 2 is a rear perspective view, taken from the bottom;

Figure 3 is a front perspective view, taken from the top, showing the covers in partially open position; and

Figure 4 is a front perspective view, taken from the top, with the covers removed.

I claim:

The ornamental design for a combination tap wrench and holder, substantially as shown and described.
